Primary Examiner — Joseph Kukella*Assistant Examiner* — Darryl J Dardenne(74) *Attorney, Agent, or Firm* — STETINA BRUNDA
 GARRED & BRUCKER(57) **CLAIM**

The ornamental design for a carafe, as shown and described.

DESCRIPTION

FIG. 1 is a top perspective view of my new design for a carafe;

FIG. 2 is a front elevation view thereof;

FIG. 3 is a right side elevation view thereof;

FIG. 4 is a back elevation view thereof;

FIG. 5 is a top plan view thereof;

FIG. 6 is a bottom plan view thereof;

FIG. 7 is a cross-sectional right side elevation view thereof along axis 7-7 of FIG. 2; and,

FIG. 8 is an exploded top perspective view thereof with a lid illustrated separated from a carafe body.

The broken lines in FIGS. 1, 2 7 and 8 is for the purpose of illustrating portions of an underside of a lid of the carafe and form no part of the claimed design.

1 Claim, 4 Drawing Sheets(56)
